UNITED STATES PATENT OFFICE.

LUCIUS W. WASHBURN, OF BOSTON, MASSACHUSETTS.

MOLD FOR CASTING CAR-WHEELS.

SPECIFICATION forming part of Letters Patent No. 254,521, dated March 7, 1882.

Application filed January 9, 1882. (No model.)

To all whom it may concern:

Be it known that I, LUCIUS W. WASHBURN, of Boston, in the county of Suffolk and State of Massachusetts, have invented certain new and useful Improvements in Molds for Casting Car-Wheels, of which the following is a specification.

The object of my invention is to provide a mold for casting car-wheels from two metals, the central or body portion being cast from a soft metal or common iron, and then, the mold being changed quickly, the tire is cast around the same from decarbonized iron or steel, which is susceptible of receiving a very hard chill.

It is found somewhat difficult to cast wheels from two metals poured at different times into the same mold, on account of the time required to make the necessary changes after the first metal cast has become partially crystallized or cooled sufficiently so as to permit of the removal of the necessary copes and stop-rings from the mold and the substitution of the extra cope and chill-ring as heretofore employed, such changes requiring sufficient time to intervene to allow the first metal cast to cool too much before the second metal can be cast therein. Thus to form a perfect union of the two metals cannot at all times be relied upon, thereby occasioning great loss of labor and material, as it is very important in the construction of this class of car-wheels that the two metals cast should form a perfect union with each other. Molds as heretofore constructed for this purpose have not only been very expensive on account of the closely-fitting joints required, but on account of the unequal expansion of the two rings of metal heretofore employed in molds of this kind, either the one expanding so as to burst the other or leaving an open space between the two, so as to permit the cast metal to enter therein, thus destroying either the mold or spoiling the wheel cast.

I am enabled by aid of my improved molds to fully overcome these and other objections; and my invention consists in the novel construction, combination, and arrangement of certain parts of the mold, as hereinafter more fully described, and set forth in the claim.

Figure 1 is a perspective view of a mold constructed according to my invention adapted to form the cast central body portion of a

car-wheel. Fig. 2 is a vertical central section of the same with that portion of the car-wheel cast therein. Fig. 3 is a similar view of the mold complete with the car-wheel and its tire cast therein. Fig. 4 is a perspective view of the chill-ring used in casting the tire. Fig. 5 is a similar view of the extra cope used in casting the tire.

A represents the lower portion of the mold, upon which rests the horizontal flange B of the metallic ring C, the interior face of which inclines inwardly, being tapering or conical from the bottom upward to the shoulder D, which serves to form a face or true surface on the rim 65 of the wheel when cast, which projects inwardly about the distance designed for the thickness of the rim of the central or body portion, E, of the wheel, the periphery thereof being cast against the inner face, C, of this stop-ring, the upper portion or projection, F, of which contacts with the ends of the arms of the cope G, and is held firmly in position temporarily by means of the vertical projecting pins J, passing through or formed upon the lugs I, extending horizontally from the outer periphery of the said base portion A, and fitting within corresponding holes formed in the lugs extending outward from the flange B of the said stop-ring, the upper portion, F, of which is secured 70 to the ends of the arms of the cope G by horizontal pins H passing through said portion F and into corresponding holes in the ends of the said arms of the cope G, whereby it is retained in position while the metal is being cast into 75 the mold thus formed.

The metal being poured through the sprue-holes near the center of the cope G forms the center or body portion, E, of the wheel being cast from soft iron, as heretofore. Now, as soon 80 as the said center or body portion, E, of the wheel has been cast and sufficiently cooled as to set at its periphery, which contacts with the interior face of the lower portion, C, of the said stop-ring, the said horizontal pins H being 85 withdrawn, the stop-ring B C F is lifted upward and removed from the said portion A, leaving the central cope, G, in place or position undisturbed, and the sand therein resting upon the said central body portion, E, just cast, 90 and by which it is supported. Now, a second metallic chill-ring, K, (shown in Fig. 4,) of

larger interior diameter than the lower portion, C, of the stop-ring removed, is instantly substituted therefor, as shown in Fig. 3, whereby the desired space is left between the interior 5 of the said chill-ring K and the periphery of the body E just cast, which serves as or forms a mold for the steel tire P, an extra cope, L, (shown in Figs. 3 and 5,) of larger diameter than the cope G, and adapted to be placed on 10 the mold with the said chill-ring K, upon which it rests. Decarbonized iron or steel is then poured through the sprue-holes s, formed through the said cope L, so as to contact with the upper outer corner or periphery of the 15 said rim of the central body portion, E, just cast, and by its greater heat remelt the said partially-cooled periphery, so as to mingle or unite therewith so perfectly as to become, when cooled, one continuous casting through- 20 out, the soft-iron central body portion and the steel or decarbonized-iron tire having a hard chilled periphery or tread. By means of the construction of the said stop-ring B F C in one continuous piece, as shown, a very considerable 25 expense is saved, and the time intervening between the first and second casting of the two metals is materially reduced, whereby a more thorough and perfect union of the same is obtained.

30 I am well aware that heretofore stop-rings have been made in sections, and having an internal circumferential groove into which the cast metal of the body of the wheel would enter, thus requiring the stop-ring to be re- 35 moved in pieces, first horizontally within the mold, then raised up therefrom vertically, consuming so much time that the cast metal first poured would become too cool to be effectually remelted by the casting of the second metal 40 or tire, thus causing great loss by imperfect union of the two metals cast at different times, as the most rapid changes of the mold between the two castings of metals are required to obtain a complete mingling or union of the tire 45 with the body previously cast.

I am also aware that heretofore a mold has been constructed for casting car-wheels from two metals cast into the same mold by the employment of a stop-ring constructed so as

to form a groove in the periphery of the body 50 first cast. Therein the stop-ring had to be formed in sections and be removed from the same, first horizontally, then lifted vertically from the mold before the casting of the second metal, wherein the time necessary to make the 55 changes required between the casting of the two metals was so great that the first metal cast would become crystallized and so cold that the second metal cast would not remelt it. Consequently "cold shots" were formed instead of 60 a union of the two metals, as is produced by my invention.

I am also aware that heretofore these defects have been sought to be removed, and for such purpose the stop-ring and cope have been formed 65 in two separate pieces of metal, the cope-rim being turned off true at its periphery and fitted outside of the metal stop-ring beneath, thereby requiring nicety of fitting and adjustment of the two parts when placed together; 70 but when the mold is so constructed the great amount of heat transmitted from the first metal cast against the inner face of the stop-ring would cause it to expand so much faster than the cool metal cope-rim extending partially outside of the said stop-ring that such unequal expansion between the two would serve 75 to break the outside cope-rim, and thereby destroy the wheel being cast and render the operation impracticable. My invention fully 80 overcomes these defects, as the cope-rim and stop-ring are formed of one continuous piece of casting or metal, and thereby caused to expand uniformly or equally throughout.

Having thus described my invention, what 85 I claim is—

The combination, with the base A and cope G of the mold, of the stop-ring consisting of the horizontal flange B and internal incline faces, F and C, united by the horizontal face 90 or shoulder D, all being formed of one continuous piece of metal, substantially as shown and described, as and for the purposes set forth.

LUCIUS W. WASHBURN.
